UNITED STATES PATENT OFFICE.

WILLIAM DANIEL DAVIS, OF NASHVILLE, ARKANSAS.

FIRE-STARTER.

1,216,780.

Specification of Letters Patent. Patented Feb. 20, 1917.

Application filed February 23, 1916. Serial No. 80,030.

To all whom it may concern:

Be it known that I, WILLIAM D. DAVIS, a citizen of the United States, residing at Nashville, in the county of Howard and 5 State of Arkansas, have invented certain new and useful Improvements in Fire-Starters, of which the following is a specification.

My invention relates to improvements in 10 fire starting machines in which coal oil, gasoline, or any combustible liquids may be used in starting domestic fires in wood or coal stoves, furnace or fire place with perfect safety and ease; and the object of my 15 improvements are, first, to provide a gas tight tank with a combination filler-plug and funnel attached, equipped with air valve, and handle with hook, and so arranged on a main stand supported by three 20 legs and adjustable to any stove or furnace by means of a flexible hollow wire or tube, as to be safe, cheap, durable, convenient and practical.

Second, to provide facilities for the 25 proper adjustment of the quantity of fuel used, and third, to so arrange a combination of improvements in a fire starter in such a compact way as to make it possible to set the machine on stove, adjust to fuel, open 30 feed valve and light in five seconds and the spraying nozzle will start fire in wood or coal in a few seconds.

I attain these objects by the mechanism 35 illustrated in the accompanying drawing, in which the figure shows a sectional view partly in elevation of the fire starter in operative position on a stove.

Similar numerals refer to similar parts 40 throughout the view which forms a part of this specification.

The main stand 9, its three legs 12, and oil tank 5, connected by feed pipe 6, constitute the frame work of the machine.

Attached funnel 2, is screwed into tank 5 45 and thus remains. The filler-plug 1, passes through funnel 2, and has hole in center and when turned to left a few rounds, a pin in lower end strikes lower end of funnel and stops, this raises a gate and allows oil to 50 pass through into tank 5, air valve 3, allows

air to pass out as oil passes in, rendering it very convenient in filling tank.

The oil passes from tank 5, down through feed pipe 6, by opening feed valve 7, thence through a gage tip 8, that adjusts the quantity of oil required without having to adjust it with valve 7. 55

The gage tip has cone at bottom and hole through cone which catches the sand and solid substance and prevents necessity of 60 frequent cleaning. The hollow wire connections 10, are screwed into main stand 9, and the flexible hollow wire 11, is fastened to connections 10, and by the use of the flexible wire, the machine is adjustable to 65 any stove or furnace.

The oil passes through the flexible hollow wire 11, to the spraying nozzle 13, and when lighted soon forms gas and the natural draft furnishes air and the combustion is 70 complete in a short time.

When fire is started cut off feed valve 7 and remove to another stove or hang up by handle and hook 4, until wanted again.

I am aware that prior to my invention, 75 fire starting machines have been made to start fires with coal oil, gasoline and combustible liquids, using a tank and burner connected with a pipe; I therefore do not claim such a combination broadly, but I 80 claim the combination in a fire starting machine having the following new and improved features:

1. A fire starter comprising an oil supply tank, a combination funnel and filler-plug 85 attached to the tank, said tank provided with an air vent, a valve controlling said vent, a combination handle and hook secured to the tank, a rigid feed pipe connected to the tank, a stand secured to the rigid feed pipe, a spraying nozzle, a flexible hollow wire connecting the spraying nozzle to the rigid feed pipe, said rigid feed pipe equipped with a feed valve, and a gage plug in the feed pipe, substantially as described. 90 95

2. A fire starter comprising an oil supply tank, a combination funnel and filler-plug attached to the tank, said tank provided with an air vent, a valve controlling said vent, a combination handle and hook se- 100

2
cured to the tank, a rigid feed pipe connected to the tank, a stand secured to the rigid feed pipe, a spraying nozzle, a flexible hollow wire connecting the spraying nozzle 5 to the rigid feed pipe, said rigid feed pipe equipped with a feed valve, and a gage plug in the feed pipe, said stand consisting of a

body and three curved legs screwed into the body in triangular position, substantially as described.

WILLIAM DANIEL DAVIS.
